Attorney.

UNITED STATES PATENT OFFICE.

NORMAN E. BASLER, OF ST. LOUIS, MISSOURI.

RAIL-ANTISPREADING DEVICE.

1,387,340.

Specification of Letters Patent.

Patented Aug. 9, 1921.

Application filed May 1, 1920. Serial No. 378,255.

To all whom it may concern:

Be it known that I, NORMAN E. BASLER, a citizen of the United States, residing in the city of St. Louis and State of Missouri, have invented certain new and useful Improvements in Rail-Antispreading Devices, of which the following is a specification.

My invention relates to rail anti spreading devices, and, has for its object to provide a device to overcome certain practical objections to, and defects in, the present form of rail anti spreading devices, and, to provide a device which will be simple in construction, durable and effective for the purpose intended.

With the above and other objects in view, the invention consists in the novel features of construction, arrangement and combination of parts hereinafter described and finally pointed out in the claims hereto appended.

Referring to the accompanying drawings forming a part of this specification wherein like characters of reference denote similar parts throughout the several views:

Figure 1, is a plan view of the invention applied to the rails.

Fig. 2, is a side elevation, partly in section, of the device applied to the rails.

Fig. 3, is a detail, in side elevation, of one of the gage shanks.

Fig. 4, is a detail, in side elevation, of one of the screw-threaded clamping shanks.

Fig. 5, is a sectional view, taken on line 5-5 of Fig. 2.

Fig. 6, is a sectional view taken on line 6-6 of Fig. 2.

Referring to the drawing, the reference character 1 designates the tread member of the rails; 2, the underfaces inclined thereof; 3, the web member of the rails, and, 4, the base member.

In carrying out the aim of my present invention I employ a pair of outer clamping members each consisting of a rail clamping jaw 6 having the base member receiving recess 7, the web engaging face 8 and the inclined tread member engaging face 9. A shank 10 extends inwardly from each clamping jaw 6 and is provided with a flat upper face 11. The inner end 12 of each shank 10 is provided with screw-threads to receive an internally screw-threaded coupling 13 for uniting the shanks. One of the shanks 10 is provided with right handed screw-threads

while the other shank is provided with left handed screw-threads and the bore of the coupling 13 is likewise screw-threaded so that by turning the coupling in one direction, with a wrench, the clamping jaws will be moved inward and by turning the coupling in the opposite direction, the clamping jaws 6 will be moved in an outward direction, as is manifest.

I further employ a pair of rail gage members each consisting of a rail clamping jaw 14 having a beveled lower face 15 to provide a base member receiving recess 16 when mounted upon the shanks 10. The jaw 14 of each rail gage member is further provided with the web engaging face 17 and the inclined tread member engaging face 18. A gage shank member 19 extends inwardly from each inner rail clamping jaw 14 and is provided with a flat lower face 20 for abutting engagement with the upper flat face 11 of each shank 10 when mounted thereon, as clearly shown in Figs. 2 and 6. The inner extremity of each gage shank 19 is provided with a suitable coupling engaging head 21 adapted to engage the end faces 22 of the coupling 13.

A pair of suitable guide loops 23 are carried by each shank 19 and they are each removably and adjustably fixed thereto by means of the set screws 24. The guide loops 23 of each shank 19 encircle the shanks 10 upon which shanks 19 are slidably mounted and tend to hold the shanks 19 from lateral displacement, as is manifest.

The clamping jaws 6 are adapted to engage the outer face of the web 3 of each rail, and also the under face of the tread member 1 and upper face of the base member 4, as clearly shown in Fig. 2. The clamping jaws 14 are adapted to engage the inner face of the web 3, of each rail, and also the underface of the tread member 1 and the upper face of the base member 4, as clearly shown in Fig. 2.

By turning the coupling 13, in one direction, it will be observed, that after the threaded ends 12 of the shanks 10 have entered the screw-threaded bore of the coupling a suitable distance the head 21 at the free end of each shank 19 will come into contact with the end faces of the coupling 13, which coupling serves to prevent the jaws 14 from approaching each other beyond a certain minimum distance which distance

determines the gage of the track. The jaws 14 are adapted to be moved outward against the inner face of the web 3 of each rail while the jaws 6 will tend to move inwardly 5 against the outer face of the web of each rail and that the further the coupling is turned, the tighter the jaws 6 and 14 will clamp the rails, as is manifest, thereby maintaining them at gage and preventing 10 their spreading at places along the railway track where they are applied to the rails.

It will be readily seen that by turning the coupling 13 in an opposite direction that the screw-threaded ends 12 of the shanks 15 10 may be disengaged from the coupling 13 and withdrawn from the guide loops 23, in transferring the parts from one place to another or in shipment.

It will be here observed that the shanks 20 19 are arranged in opposed relation upon opposite sides of the coupling and likewise the shanks 10 upon which the shanks 19 are mounted and guided by means of the guide loops 23.

25 From the foregoing description, it is evident that I provide a durable and efficient rail tie clamp, or anti spreading device which will positively prevent lateral displacement or spreading of rails at places 30 along a track where they are applied.

The many advantages of the herein described invention will readily suggest themselves to those skilled in the art to which it appertains.

35 I do not desire to be understood as limiting myself to the exact details of construction and arrangement as herein described and illustrated, as it is manifest that variations and modifications may be made without 40 departing from the spirit and scope of my invention and the terms of the following claims, hence I wish it to be understood that

I reserve the right to make any such changes, or modifications as may fairly fall within

45 the scope of the appended claims when fairly construed.

What I claim is:

1. An anti-spreading device for railways comprising a pair of shanks having their upper faces flat and their inner ends screw-threaded, a coupling for uniting said screw threaded shanks, a rail engaging head at the outer end of each screw threaded shank, a gage shank having a flat lower face mounted upon each screw threaded shank, a rail engaging head at the outer end of each gage shank, a head at the inner end of each gage shank having abutting engagement with the end faces of the coupling and guide loops 50 removably fixed to the gage shanks and encircling the screw threaded shanks to prevent lateral displacement of the gage shanks 55 upon the screw threaded shanks.

2. A rail anti-spreading device comprising a pair of shanks having flat upper faces and 60 screw threaded at their inner ends, rail engaging jaws at the outer ends of said shanks having surfaces for engaging the outer underface of the tread portion of the rails, the outer face of the webs thereof and the 70 outer upper face of the base members of the rails, gage shanks mounted upon the aforesaid shanks, rail engaging jaws at the outer end of said gage shanks having surfaces for engaging the inner undersurface 75 of the tread portion of the rails, the inner face of the webs thereof and the inner upper face of the base members of the rails, a head having a flat face at the inner end of each gage shank, a coupling for uniting the screw 80 thread shanks for drawing the jaws thereof toward each other and serving to prevent the jaws of the gage shanks from approaching each other beyond a certain minimum distance which distance determines the gage 85 of the track and means to prevent displacement of the gage shanks upon the screw threaded shanks.

In testimony whereof, I have hereunto signed my name to the specification.

NORMAN E. BASLER.
